UNITED STATES PATENT OFFICE.

CHARLES WORTH TURNER, OF NEW YORK, N. Y.

PROCESS OF DISTILLING HYDROCARBON OIL.

1,151,422.

Specification of Letters Patent. Patented Aug. 24, 1915.

Original application filed July 21, 1908, Serial No. 444,674. Divided and this application filed October 26, 1912. Serial No. 727,925.

To all whom it may concern:

Be it known that I, CHARLES W. TURNER, a citizen of the United States, residing in the borough of Kings, Brooklyn, New York city, in the county of Kings and State of New York, have invented certain new and useful Improvements in Processes of Distilling Hydrocarbon Oil, of which the following is a specification.

10 This invention relates to a process for distilling petroleum and other hydrocarbon oil and obtaining products of various gravities.

15 The principal object of my invention is to provide for economically and rapidly distilling hydrocarbon oil, such as petroleum or a distillate thereof, by subjecting it, together with steam or water, to heat and high pressure while circulating through heated 20 coils, whereby part of the heavier hydrocarbons will be split or cracked to form lighter distillate liquid products, such as naphtha, benzin and gasoline.

25 One of the special objects of my invention is to provide improvements in the process, whereby earthy or mineral matter and asphaltum, or other heavy carbonaceous material may be separated and deposited from the petroleum or other hydrocarbon 30 while it is being preliminarily heated and at different stages in its passage through the vaporizing decomposing and recomposing coils.

35 The present invention embraces certain improvements in the process of treating oil whereby petroleum of low gravity or other hydrocarbon oil may be successfully subjected to the distilling and cracking operations for increasing the yield of light distillates, such as naphtha, benzin, gasoline, etc., without danger of the coils and connecting pipes becoming clogged or choked with carbonaceous deposits.

40 The matter constituting my invention will be defined in the claims.

I will now describe my process by reference to the accompanying drawing, in which—

45 Figure 1 represents a side elevation, with parts in section, of the distilling, decomposing and recomposing part of the apparatus. Fig. 2 represents an elevation, with parts in section, of the separating and condensing tanks for obtaining various liquid products 50 of different specific gravities.

The distilling part of the apparatus comprises two columns of coils 1 and 2 composed of different sections of coils, suitably disposed separating drums of comparatively large diameter and the necessary connecting pipes for effectively and rapidly carrying out the process of distilling crude petroleum or other hydrocarbon oil. In the column 1 the different sections of coils are superimposed one above another within a heat-retaining jacket 8. The steam-generating and superheating coil 3 is preferably placed at the top of the casing where the temperature is usually the highest, and the oil vaporizing coil 5 is located immediately below the same 60 so that the steam and oil vapor may be readily brought together in a mixing pipe. Between the outer oil feed tank and the coil 5 I have found it advantageous to interpose an oil heating and separating drum 4, which, preferably, extends from the base of the column up through all of the coils to near the top of the jacket 8, as shown in Fig. 1. The coils are preferably constructed of pipe having extra thick and strong walls, adapted to stand pressure of several hundred pounds to the square inch. In the apparatus which I have in use the pipe is two inches in diameter, while the heating and separating drum 4 is about five inches in diameter and may be of a larger diameter, up to ten inches or more. This heating and separating drum 4 serves the important purpose of preliminarily heating the crude oil and at the same 65 time permitting the contained mineral matter and asphaltum, or other heavy carbonaceous material, to settle into the lower and colder end from which, at suitable intervals, such matter is drawn off through valve 4^a and discharged through pipe 31 into a tank 32. Below the oil vaporizing coil 5 is located a coil 6 for mixing steam or water and oil vapor, and at the base of the column is located a combining and superheating coil 7. 70

The tanks for supplying water and oil under pressure and the various feed and connecting pipes are constructed and arranged as follows: The water supply tank 9 and two oil supply tanks 17 are in practice located on a suitable foundation and are connected at their lower ends with a water force-pump 33 having a pipe 34 and branches, provided with valves 35, 36 and 37, connecting with each tank. The water supply being shut off from the oil tanks by 75

closing valves 36 and 37, both of the tanks 17 may be first filled with oil, such as crude petroleum, in any desired manner, and when it is desired to force oil into the vaporizing coil, water will be admitted under pressure into one of the tanks by opening valve 36, thereby forcing oil out through the upper feed pipe into separating drum 4 and thence to the coil. The water feed pipe 10 connects 10 with the top of tank 9 and with the base of the coil 3. This pipe is provided with the stop valves 11 and 12, an intermediate check-valve 13 and a test cock 14. From the top of coil 3 a steam or water discharge pipe 15 15 extends out through the jacket 8 and downward to a mixing pipe 16, with which also connects the oil or vapor pipe 27. In order to determine approximately the quantity of water supplied through the pipe 10, valve 12 20 is closed, the test cock 14 fully opened and the valve 11 partly opened and adjusted so that the desired flow will be discharged through the test cock; this having been ascertained by observation, the test cock 14 is 25 closed and valve 12 opened, leaving valve 11 at the proper adjustment for feeding the desired quantity or proportion of water into the coil 3. The check valve 13 prevents the back flow of water through pipe 10. With 30 the tops of the oil tanks 17 connect two feed pipes, 18 and 18^a, which unite with the single feed pipe 21, and said pipes 18 and 18^a are provided, each with a valve 19 and 20. The oil feed pipe 21 connects with the heating 35 and separating drum 4 above its lower end and is provided with the stop valves 22 and 23, the intermediate check-valve 24 and a test cock 25. The flow of oil through pipe 21 is regulated by means of test cock 25 and 40 adjustment of valve 22 as above described with reference to the test cock and valve on the water pipe 10. With the upper end of the heating and separating drum 4 connects the oil discharge pipe 26 which extends 45 downward and connects with the base of the oil-vaporizing coil 5. An oil or vapor discharge pipe 27 leads from the top of coil 5 and connects through a T-fitting with the mixing pipe 16 which leads into coil 6 for 50 mixed steam or water and oil or vapor. At the base of coil 6 a discharge pipe 28 connects with a separating drum 29 which is provided at its base with a discharge pipe, having a valve 30, opening into the main 55 discharge pipe 31 connecting with the receiving tank 32. Any tarry or other thick carbonaceous matter which may form in coils 6 will be blown into the separating drum 29 and after a sufficient quantity of 60 heavy hydrocarbon accumulates in such drum it may be discharged by opening valve 30. Pipe 38 connects near the top of drum 29 and conducts mixed steam and oil-vapor into the top of the combining and 65 superheating coil 7 from the base of which

leads the outlet pipe 39, connecting with the separating drum 43. A pipe and valve 42 leading from pipe 52, connects with the burner 41 for supplying fuel-gas. In practice, I burn at the burners 41 and 41^a part of 70 the gaseous mixture which passes by pipe 54 from the decomposing and recomposing coil 53. The vapor or gas will pass from coil 7 into the separating drum 43. The heavier hydrocarbon or tarry matter will be separated in drum 43 and may be discharged 75 therefrom by opening valve 44. A vapor-gas outlet pipe 45 connects with the top of drum 43 and with the top of the combining and decomposing coil 46 in the column 2, where cracking is effected. The coil 46 connects with a separating drum 48 from which a pipe 47 connects with the top of coil 46^a, from the base of which a pipe 47^a connects with a separating drum 50, having 80 at the bottom an outlet pipe and valve 49 which connects with the drain pipe 31 leading to tank 32. A vapor-gas outlet pipe 51 passes from drum 50 up through the column of coils to the top of an upper section of coils 53 in which the operations of 85 still further decomposing and recomposing hydrocarbons are effected. From the base of this coil extends a vapor-gas outlet pipe 54 leading to the first separating and condensing tank 60. A pipe 52 may connect with pipe 54 for conducting fuel-gas to the 90 burners 41 and 41^a.

Special oil burners may be used, in which oil and water are fed to heating coils and the resulting vapor-gas burned, instead of drawing off vapor-gas from pipe 54. The flame and hot products pass from the burners up through the columns of coils and thence down between the coils and the heat-retaining jackets 8, from the lower ends of which the spent products escape. Combustion of vapor-gas being perfect within the heating jackets, no smoke or sooty matter 100 passes out from the base of the jackets. 105

The separating and condensing tank 60 is provided at the bottom with a draw-off pipe and valve 70 leading to a cooling coil 56 located in the water tank 57. To the top of tank 60 connects a vapor pipe 90, having a 110 valve, which extends downward and connects at about the middle height with the succeeding separating tank 61. A separate vapor outlet pipe 80 connects centrally with the top of tank 60 and extends downward below 115 the middle portion thereof where its end is open for conducting off a different density of vapor from that which passes off through pipe 90. In practice, I provide a series of separating and condensing tanks 60, 61, 62, 120 63, 64, 65 and 66, and I may employ sixteen or more of such tanks for separating and condensing hydrocarbon distillate of different gravities. These tanks are connected by pipes and valves 71 to 76, to cool- 125 130

ing coils like that shown at 56 in the water tank 57, and each of said coils is provided with a draw-off pipe 56^a. The tanks are connected in series by pipes and valves 90, 91, 92, 93, 94, 95, leading each from the top of one tank to the middle portion of the succeeding tank, and each tank has a separate vapor discharge pipe, 80, 81, 82, 83, 84, 85, to the end of the series, which connect 10 with separate condensing devices, not here shown.

I preferably connect with each of the water and oil tanks a pressure gage 100 and maintain in said tanks a pressure of about 15 100 pounds to the square inch. I also connect to the separating drum 29 a pressure gage 101, which will indicate the vapor pressure in the coils 6 and 7. This pressure is preferably about 60 pounds to the square 20 inch. It will be understood that with these high pressures and with a sufficiently high temperature, which may be from 400° to 800° Fahrenheit, in the coils 6 and 7, the circulation of water, oil and combined 25 vapors will be very rapid and that distillation will be effected with corresponding rapidity. In the column 2 I preferably carry the temperature up to a degree between 1000° and 1200° or 1400° Fah. A 30 pressure gage 102 is also applied to separating tank 60.

The apparatus having been constructed and connected substantially as above described and shown in the drawings, and the 35 tanks 9 and 17, respectively, filled with water and petroleum, the operation of distilling and cracking the hydrocarbon, to form products of different gravities and then separating such products, may be conducted as follows:

The columns of coils may be primarily heated by supplying fuel oil to the burners, or by burning any waste material saturated 45 with oil at the base of the columns in the jackets 8. The temperature having been raised to the desired degree in the jackets, the pump 33 will be started, thereby forcing water into the base of tank 9 and one of the tanks 17; now by properly adjusting the 50 valves in the supply pipes as previously described, water will be supplied under pressure to the steam generating coil 3 and oil will be supplied under pressure to the pre-heating and separating drum 4 and thence 55 by pipe 26 to the oil-heating and vaporizing coil 5. As soon as a sufficiently high degree of heat has been attained, superheated water or steam will pass by pipe 15 to the mixing pipe 16, and at the same time oil or 60 vapor will be passed by pipe 27 to said mixing pipe 16, and the mixture will be forced through coil 6 where the steam and oil or vapor will be more intimately mixed and heated and then discharged through pipe 28 65 into the separating drum 29. Here the

heavier hydrocarbons, tarry matter and earthy material or other impurities will be arrested and settle to the bottom, while the lighter vapors or liquids will be conducted by pipe 38 into the combining and super-heating coil 7 in which will be produced vapor-gas. The heavy hydrocarbons, containing paraffin and tarry matters which may settle in the drums 4 and 29 will be, at suitable intervals, drawn off, and conducted 70 by pipe 31 to the receiving tank 32. The vapor gas discharged from coil 7 through pipe 39 into the separating drum 43 will also part with the heavy hydrocarbons which will settle in said drum, and may be 75 drawn off through pipe and valve 44 and conducted by pipe 31 to tank 32. The vapor-gas passing off from drum 43 will be conducted through the coil 46, where it will be subjected to a high heat, usually about 80 800° Fahrenheit, thereby causing the heavier hydrocarbons to be split up or cracked into hydrocarbons of light specific gravity. I therefore obtain a greatly increased yield of lighter hydrocarbon oils, 85 such as naphtha and gasolene, from crude petroleum. Paraffin, naphthalene and tarry matter which may be formed will be separated in the drums 48 and 50. By successively causing separation of heavy carbonaceous matter, including paraffin and 90 naphthalene, a superior quality of lubricating oil will be collected in the first two or three separating and condensing tanks 60, 61, 62, of the series. In the succeeding tanks 100 63, 64 and 65, a high grade of illuminating oil or kerosene will be separated and deposited. In the succeeding tanks of the series, which may be of any desired number, there will be separated various gravities of 105 lighter oils and any desired number of these light oils such as benzin, gasolene, etc., may be separately drawn off and stored.

This application is a division of my co-pending application, Serial Number 444,674, filed July 21, 1908, covering the apparatus herein shown and described, for which Patent No. 1,046,682 was issued Dec. 10, 1912.

Having described my invention, what I claim, and desire to secure by Letters Patent, is:

1. The process of distilling and separating hydrocarbon oil into distillates of different gravities, which consists in preliminarily heating a body of oil and causing separation and deposit of heavy hydrocarbon or asphaltum and tarry matter, forcing the separated and heated lighter oil into a vaporizing coil and at the same time forcing 110 water into a separate vaporizing coil, forcing the resulting oil and water vapors together under pressure through a superheater at a temperature to cause cracking of the 115 hydrocarbon into lighter products, then re- 120 125 130

leasing the vapor products from pressure and heat and separating the different liquid gravities.

2. The process of distilling and separating hydrocarbon oil into distillates of different gravities, which consists in forcing oil and water and the resulting vapors under pressure through heated coils at intervals, releasing the combined liquids or vapors from pressure for causing separation and deposit of the heavier hydrocarbons, then subjecting the remaining lighter hydrocarbons and water vapor under pressure to a higher or cracking temperature, thereby cracking the hydrocarbon to form hydrocarbons of lighter specific gravities, then releasing the products from pressure and heat and separating the different gravities.

3. The process of distilling hydrocarbon oil and forming different gravities, which consists in subjecting mixed oil and water vapors alternately to pressure and heat and to expansion and cooling, thereby cracking the lighter constituents to form an increased

percentage of hydrocarbons of light specific gravities, and at the same time depositing the heavier constituents, and then releasing the vapor products from pressure and heat and separating the different gravities.

4. The process of distilling hydrocarbon oil and forming different gravities, which consists in subjecting oil combined with water vapor to pressure and heat, then to expansion at a reduced temperature, thereby separating the heavier constituents, then subjecting the lighter constituents or products to pressure and heat above the distilling temperature to cause cracking, into hydrocarbons of lighter gravity, then releasing the resulting products from pressure and heat and separating the different gravities.

In testimony whereof I affix my signature in presence of two witnesses.

CHARLES WORTH TURNER.
